(57) **CLAIM**

The ornamental design for a combined sandwich cutter and sealer, as shown and described.

DESCRIPTION

FIG. 1 is a perspective view of a combined sandwich cutter and sealer, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a perspective view thereof, shown without the insert for ease of illustration;

FIG. 9 is a top plan view thereof, shown without the insert for ease of illustration;

FIG. 10 is a bottom plan view thereof, shown without the insert for ease of illustration;

FIG. 11 is a front elevation view thereof, shown without the insert for ease of illustration;

FIG. 12 is a rear elevation view thereof, shown without the insert for ease of illustration;

FIG. 13 is a right side elevation view thereof, shown without the insert for ease of illustration;

FIG. 14 is a left side elevation view thereof, shown without the insert for ease of illustration;

FIG. 15 is a perspective view thereof, shown without the base for ease of illustration;

FIG. 16 is a top plan view thereof, shown without the base for ease of illustration;

FIG. 17 is a bottom plan view thereof, shown without the base for ease of illustration;

FIG. 18 is a front elevation view thereof, shown without the base for ease of illustration;

FIG. 19 is a rear elevation view thereof, shown without the base for ease of illustration;

FIG. 20 is a right side elevation view thereof, shown without the base for ease of illustration; and,

(Continued)

FIG. 21 is a left side elevation view thereof, shown without the base for ease of illustration.
